UNITED STATES PATENT OFFICE

GLENN A. MENGLE, OF BROCKWAY, PENNSYLVANIA, ASSIGNOR TO BROCKWAY SALES COMPANY, OF BROCKWAY, PENNSYLVANIA, A CORPORATION OF PENNSYLVANIA

DESIGN FOR A JAR

Application filed February 7, 1933. Serial No. 47,144. Term of patent 3½ years.

To all whom it may concern:

Be it known that I, GLENN A. MENGLE, a citizen of the United States, residing at Brockway, in the county of Jefferson and State of Pennsylvania, have invented a new, original and ornamental Design for a Jar, as shown in the accompanying drawing and described in the following specification.

Figure 1 is a front elevation;

Figure 2 is a side elevation; and

Figure 3 is a top view.

Referring to the drawing, the front and

back of the jar form parallel panels with rectilinear edges, the walls of the jar converging from these edges toward the sides.

The handle aperture is within the boundary of the jar and has a straight wall coinciding with the plane embracing the adjacent edges of the front and back panels

I claim:

The ornamental design for a jar substantially as shown and described.

GLENN A. MENGLE.
